UNITED STATES PATENT OFFICE.

WILLIAM BOUGHTON, OF CALEDONIA, OHIO.

VEHICLE-SPRING.

SPECIFICATION forming part of Letters Patent No. 310,175, dated January 6, 1885.

Application filed June 2, 1884. (No model.)

To all whom it may concern:

Be it known that I, WILLIAM BOUGHTON, a citizen of the United States, residing at Caledonia, in the county of Marion and State 5 of Ohio, have invented certain new and useful Improvements in Vehicle-Springs; and I do declare the following to be a full, clear, and exact description of the invention, such as will enable others skilled in the art to which it applies 10 to make and use the same, reference being had to the accompanying drawings, and to the letters and figures of reference marked thereon, which form a part of this specification.

15 My invention relates to side-bar vehicles; and it consists in the novel construction, combination, and arrangement of the several parts, as will be hereinafter more fully described and claimed.

20 In the drawings, Figure 1 is a plan, Fig. 2, a side, and Fig. 3 an end view, of my improved gear. Fig. 4 is a modified form of hanger and side bar. Fig. 5 represents a modified form of side bar. Figs. 6 and 7 represent detail views of clip. Fig. 8 represents a modified form of side-bar hanger, all of which will be described.

25 The bars or bolsters A support the bolster-springs B. These springs are preferably made in the form shown, with their middle portion bolted to the bolsters and their ends elevated above the same. The ends of these springs are bent to form the eyes B', through which pass the bolts which support 30 the hangers, presently described.

35 The side bars, C, may be made in any desired form, and are suspended at their ends by hangers C' from the ends of bolster-springs B. These hangers may be bent in a curve up 40 from the ends of the side bars, as shown in Figs. 1 and 2, or may be at right angles to the side bars, as will be understood from Figs. 4 and 5.

45 The plates C² of the hangers, it will be seen, form, practically, the side bars of a spring-clip, and the spring is secured thereto by a transverse bolt, C³, which clamps the spring between the side bars of the clip. I find it desirable and advantageous to provide these bars 50 and those of the other spring-clips presently described with lugs or ears D, which project

inwardly from the upper ends of the arms of the clip over the eye of the springs and bearing thereagainst, as shown. These ears serve to prevent damage to the eye of the spring 55 and prevent its being broken or injured in the jarring of the vehicle over rough roads. As the friction of the eye of the spring against the side arms of the clip will wear itself and said arms, I prefer to so form the clip that its 60 arms may be adjusted to and against the spring-eye, so as to take up all frictional wear and enable the securing of a firm fit at all times. This adjustment is secured in the construction shown in Figs. 1 and 2 by setting 65 the upper bar of the hanger spring-clip toward the spring-eye, as will be appreciated.

In the construction shown at the right in Fig. 4 the arms of the clip which clamps the bolster-spring to the side bar have feet or 70 base-plates C⁴ C⁴, movable one upon the other, as will be understood from Fig. 7, so as to secure the desired adjustment, which feet are clamped to the side bar by the ordinary fastening-clip shown. In Fig. 5 the arms of the 75 spring-clip are sleeved on and movable along the side bar, and may be adjusted by means of the transverse bolt, as will be understood. In the connection of the body-springs with this form of side bar I sleeve the eyes of the 80 spring on the side bar and secure it by the clips E, which have the ears D, and are adjustably secured by means of the set-screws E', as will be understood from said figure.

Except for the purposes of adjustment, as 85 before described, the clips might be made as shown in Figs. 6 and 8. The body-spring supports are formed of the arms or clip-bars F, secured at one end to the side bars, and extend outward therefrom, and have ears D formed 90 on their outer ends. The body-springs G have their ends passed under the side bars and secured to the outer ends of the clip-arms F, and secured at a point beyond the side bars, as shown. By this construction I am able to 95 use a long spring with a narrow set of side bars, and these side bars swing on the connection with the bolster-springs as the body-springs are depressed, as indicated in Fig. 3. I prefer to swing the side bars from the 100 ends of the bolster-springs, as described, as thereby greater elasticity and ease are given

the device; but it is manifest that where desired the side bars may be swung from rigid supports.

By the construction described I provide an easy-riding vehicle, and the clips are so formed as to protect the springs and take up all wear on themselves and the springs, so as to at all times secure a snug fit of the parts, as is desirable.

Having thus described my invention, what I claim, and desire to secure by Letters Patent, is—

1. The combination of the side bars, the spring-supports secured rigidly to and projected laterally outward from the side bars, and the body-springs having their extremities supported on the outer ends of the supports, substantially as set forth.

2. A clip for vehicle-springs, having its side bars or arms provided at their outer ends with inwardly-projected ears, substantially as set forth.

3. The combination of the bolster-springs, the side bars having their ends supported on

and depending from the said springs, the 25 spring-supports secured rigidly to and projected laterally outward from the side bars, and the body-springs having their extremities supported on the outer ends of the supports, substantially as set forth. 30

4. A clip for vehicle-springs, having its side bars or arms provided at their outer ends with inwardly-projected ears, and at their opposite ends with inwardly-projected feet or base-plates, movable one upon the other, substantially as set forth. 35

5. The combination, with the swinging side bars, of the spring-supports rigidly secured to said bars, and the body-springs having their extremities secured on said supports, substantially as set forth. 40

In testimony whereof I affix my signature in presence of two witnesses.

WILLIAM BOUGHTON.
